UNITED STATES PATENT OFFICE.

OLIVER D. HOGUE, OF BROOKLINE, MASSACHUSETTS, ASSIGNOR TO GEORGE H. MAXWELL, OF PHOENIX, ARIZONA.

SHOE-BOTTOM-FILLING MACHINE.

1,385,486.

Specification of Letters Patent. Patented July 26, 1921.

Application filed November 5, 1919. Serial No. 335,860.

To all whom it may concern:

Be it known that I, OLIVER D. HOGUE, a citizen of the United States, and resident of Brookline, in the county of Norfolk and 5 State of Massachusetts, have invented an Improvement in Shoe-Bottom-Filling Machines, of which the following description, in connection with the accompanying drawings, is a specification, like letters on the 10 drawings representing like parts.

My present machine is intended primarily for use with a hot filler, preferably the kind set forth in U. S. Patent No. 861,555 of July 30, 1907, which even when hot is only sluggishly fluid and hence tends to flow slowly instead of rapidly. The expert hand operator, however, has attained such skill and speed that an automatic or semi-automatic machine must operate with extreme rapidity 20 in order to compete successfully with the hand operator. To this end therefore I have provided a machine which combines in its use the skill of the operator and convenient filler delivery mechanism for accelerating 25 the delivery and means for distributing, leveling and condensing the filler properly in the shoe bottom. All this is so combined and coördinated that the operator can get the benefit of the use of both hands, one 30 hand in manipulating the shoe while the other hand manipulates the delivery end of the machine. Preferably the delivery opening is controlled by the shoe (as herein provided, in the hand of the operator) and the 35 filler delivering or ejecting mechanism is normally quiescent but is rendered instantly operative by the movement of the valve or delivery controlling device. In other words my machine provides an ejector normally 40 quiescent but rendered operative by the opening of the delivery orifice which, being under the control of the operator, enables the operator to control at all times the amount of filler delivered.

45 Further features, combinations and advantages of my invention will be set forth at length in the following detailed description taken in connection with the accompanying drawings in which I have illustrated the preferred embodiments of my invention. In the drawings—

Figure 1 is a central vertical cross-sectional view facing the front of the machine,

Fig. 2 is a horizontal sectional view taken approximately on the line 2—2 Fig. 1. 55

Fig. 3 is a vertical transverse sectional detail on line 3—3 Fig. 2.

Fig. 4 is a vertical transverse sectional detail taken on the line 4—4 Fig. 2.

At the upper end of the machine as herein shown is a hopper 1 of any suitable size and shape maintained properly warm by any suitable means as by a steam or hot water jacket 2 and at the lower end thereof is a delivery portion herein shown as a tube 65 3, also steam jacketed as indicated at 4. This tube 3 carries at its lower end a shoe or casting 5 shown as screw threaded thereon at 6 and having sloping walls 7, 8 on its interior affording a restricted outlet or 70 nozzle opening 9 closed by a valve 10 normally held downward in closing position by a spring 12. This valve has a downwardly projecting stem or finger 13 in position to be engaged by the bottom of the shoe when 75 the shoe is pressed upwardly against the same to open the nozzle for the ejection of filler. Within the tube 3 is an ejector which may be of any convenient construction, being herein shown as a screw or worm conveyor 14 for giving a sudden downward impulse to the filler in the tube whenever the screw is rotated. This screw is operated by a rod 15 and a drive pulley 16, the latter running normally idle and the rod 15 being herein shown as provided at its upper 80 end with a magnetic clutch 17. This clutch may be of any usual kind and therefore is not herein shown in detail. The clutch is connected by a circuit 18, 19 whose poles 90 20, 21 are in position to be engaged by a circuit closer or contact plate 22 mounted in insulated position on the rear projection 23 of the arms 24 which carry the valve 10 pivoted at 25 to the casting 5. Thus whenever the operator strikes the bottom of the shoe up against the stud or finger 13 he instantly opens the orifice by raising the valve 10 and at the same instant closes the circuit of the electric clutch and gives a sudden start or ejecting impulse to the screw so that the filler is forcibly shot out into the shoe and he can therefore get the required amount of filler almost instantly into the shoe bottom for filling the shoe bottom; and 105 thereupon he immediately lowers the shoe

sufficiently to permit the valve to close the orifice and break the circuit of the ejector so that the screw 14 stops.

At one side herein shown as at the right hand side of the filler orifice is a projecting arm 26 maintained suitably warm by any convenient means herein shown as by a coil 27 and shown as having a V shape in cross section; see Fig. 3; with opposite slanting walls 28, 29 and an intermediate edge or V 30. At the opposite side of the orifice is a flat plate 31 also heated by suitable means as by a coil 32. Thus when the operator has caused the desired amount of filler to be deposited in the shoe bottom in a small heap which may be elongated in its delivery simply by sliding the shoe lengthwise under the orifice, he instantly levels down this heap of filler by engagement with the arm 26 and then strikes the shoe bottom with its loosely leveled filler upward against the hot plate 31 which condenses the filler.

To enable the operator to bring all the aforesaid mechanism into the most speedy coöperation on the shoe bottom I have provided the lower end of the apparatus with a handle 33 and have mounted the lower end and ejector apparatus on a universal joint 34. The screw 14 and rod 15 are connected also by universal joint 35. Thus as soon as the operator has caused the right amount of filler to be deposited in the shoe bottom he starts to move the shoe toward the right with his left hand and at the same time with his right hand grasping the handle 33 he swings the arm 26 toward the left to meet the shoe and by a deft movement of shoe and handle causes the arm 26 to perform its leveling and spreading movement and then by an opposite movement of the arm and shoe he brings the plate 31 and shoe into forcible contact which condenses the filler and completes the leveling operation.

In practice the hopper 1 is loaded with filler which is brought to the desired degree of plasticity or semi-fluidity. Then the operator seizes the shoe in the usual manner in his left hand and strikes it against the stud or finger 13 which raises the valve 10, thereby opening the orifice 9 and at the same time starting the ejector 14 which forcibly ejects the filler in the amount desired according to the control of the operator. This control is accomplished by lowering the shoe at the critical moment which closes the orifice and stops the ejector. He then swings the shoe toward the arm 26 and swings the arm toward the shoe so that the two come into coöoperating leveling relation instantly and this is followed by an opposite swinging movement which brings the shoe bottom and plate 31 into proper pressing relation to each other. The arm 26 performs its function of smoothing and leveling with facility in cooperation with the

tipping upward more or less of the shoe bottom to coöperate with the slanting walls 28, 29 of the arm. The object of this construction is to enable the operator to shove the filler conveniently forward or backward or to one side or the other side in the shoe bottom cavity and at the same time smooth it down so as to insure that every point of the shoe bottom cavity is properly filled.

As already intimated, my invention is capable of a wide variety of mechanical embodiments and accordingly I wish it understood that I am not limited to the specific construction herein set forth as the preferred embodiment. My invention is accordingly further described in the form of claims as follows:

1. A shoe bottom filling machine, comprising a filler holding chamber having a delivery orifice, combined with means for controlling said orifice and means for suddenly ejecting the filler therefrom, both of said means being under the control of the operator.

2. A shoe bottom filling machine, comprising a filler holding chamber having a delivery orifice, combined with means for controlling said orifice and means for suddenly ejecting the filler therefrom, said two mechanisms having provision for enabling the operator to simultaneously control them both and thereby control the amount of filler delivered to the shoe bottom.

3. A machine of the kind described, comprising a filler holding chamber having a delivery portion provided with a delivery orifice, ejecting mechanism in said delivery portion normally idle, a valve for said orifice under the control of the operator, and coöperating means actuated by the movement of the valve for starting said ejecting mechanism.

4. In a machine of the kind described, holding means for containing the filler to be applied, said holding means having a discharge orifice, normally idle ejecting means adjacent said orifice, and means under the control of the operator for starting the ejector upon the application of a shoe in position to be filled.

5. In a machine of the kind described, a filler chamber having a discharge orifice, ejecting means normally idle but operative to eject when the orifice is open for ejecting filler when the orifice is open, means for closing and opening said orifice, and a stationary molding arm projecting forward from one side of said orifice, said arm having a depending under side shaped to aid the shifting of the filler in the shoe bottom.

6. In a machine of the kind described, a filler chamber having a discharge orifice, ejecting means normally idle for ejecting filler when the orifice is open, means for closing and opening said orifice, and a sta-

tionary molding arm projecting forward from one side of said orifice, said arm having a depending under side shaped to aid the shifting of the filler in the shoe bottom, 5 and a heated condensing member extending laterally from the opposite side of said orifice.

7. In a machine of the kind described, a 10 filler chamber having a discharge orifice, ejecting means normally idle for ejecting filler when the orifice is open, means for closing and opening said orifice, and a stationary molding arm projecting forward from one side of said orifice, said arm having 15 a depending under side shaped to aid the shifting of the filler in the shoe bottom, and a heated condensing member extending laterally from the opposite side of said orifice, the portion of said chamber which 20 contains said orifice arm and member being mounted for movement under the control of the operator.

8. In a machine of the kind described, a 25 filler chamber having a prolonged lower portion mounted thereon for swinging movement and provided at its lower end with a discharge orifice, a valve for controlling said orifice and a handle to enable the oper-

ator to control the movements of the orifice and thereby position the filler discharged 30 therefrom into the shoe bottom.

9. In a machine of the kind described, a 35 filler chamber having a lower portion movable with relation to the upper portion under the control of the operator and provided with a discharge orifice for the discharge of the filler into the shoe bottom, means permitting the operator to control the movement of said lower portion, and a leveling arm projecting from adjacent said nozzle 40 and movable with said lower portion under the control of the operator.

10. In a machine of the kind described, a 45 filler chamber having a discharge orifice, a valve for controlling said orifice, a filler ejector adjacent said valve normally idle, and driving means for said ejector including a clutch responsive to the opening of the valve for starting the ejector.

In testimony whereof I have signed my 50 name to this specification in the presence of two subscribing witnesses.

OLIVER D. HOGUE.
